UNITED STATES PATENT OFFICE.

LESTER B. STROUT, OF CHICAGO, ILLINOIS, ASSIGNOR TO WOODWARD & COCHEY MANUFACTURING COMPANY, OF CHICAGO, ILLINOIS, A CORPORATION OF ILLINOIS.

FINISHING WELT.

Application filed September 20, 1924. Serial No. 738,954.

This invention relates to finishing welts, and a method of making the same, and among other objects aims to provide a welt which is relatively inexpensive to manufacture.

5 The invention may be understood by reference to one illustrative embodiment shown in the accompanying drawings, in which:

Fig. 1 is a sectional elevation of apparatus for making welt according to the invention;

Fig. 2 is a sectional plan view of the same;

Fig. 3 is a section on line 3—3 of Fig. 1;

Fig. 4 is a perspective view of the folder with the parts of a welt being folded 15 thereby;

Figs. 5, 6 and 7 are sections on lines 5—5, 6—6 and 7—7 respectively of Fig. 1, showing the manner in which the welt parts are folded together;

20 Fig. 8 is an enlarged sectional view of the completed welt; and

Fig. 9 is a similar view of the welt shown attached to a support.

It is to be understood that the illustrative 25 form shown in the drawings is simply one embodiment of the invention; and that in the following explanation of that specific form, the described details of structure and organization are merely exemplary.

30 The apparatus shown for the purpose of illustrating the method of the invention includes generally a folder for assembling the parts of the welt, means for forming the assembled welt into the desired final shape, and 35 means to unite the parts.

Referring to Figs. 1 and 2, the folder shown comprises a plate or base 10 on which is secured a tapering shell 11, constructed and arranged for longitudinal travel of the 40 welt parts therethrough from the larger end to the smaller, to effect automatically the assembling of said parts. The welt is made from a flexible cover 12, conveniently of imitation leather, a central core body 13 of some 45 deformable material as loosely twisted jute fibres, and a pair of smaller cores 14 for the marginal beads. A jute fibre is advantageous because it is very easily formed to the required contour and because it is less expensive than preformed cores of many other materials. Strips of inexpensive hard twisted paper may be employed for the cores 14.

As shown in Figs. 1, 2 and 4, the welt parts

are fed into the folder with the cover 12 surrounding the cores and with the core 13 between the smaller cores 14. The folder has two guides 15, 16, at its end for the cores 14 (Fig. 5), and a longitudinal fin 17 extending from guide 15 for the principal part of the length of the folder, to segregate one 55 of the cores 14 from the large core 13 during the assembling process. By the folder shown and described, the covering 12 is encircled about the three cores 13, 14 individually, as illustrated progressively in Figs. 5, 6 and 60 7 and at the opposite sides of Fig. 4; and the originally round central core 13 is initially shaped somewhat by the oval form of the discharge end of the folder. To reduce the friction of the passage of the cover strip 12 65 and core 13 through the folder, it may be cut away at the top, as shown at 18 in Figs. 2 and 4.

As the assembled welt issues from the folder, it passes between a pair of guides 19 projecting from the folder (Fig. 2), and thence directly to the mechanism for flattening the welt and for uniting its parts. In this instance the mechanism for flattening the welt forms part of a sewing machine, which 70 75 stitches the cover strip and cores together under sufficient pressure to effect a permanent deformation of the inelastic jute fibre core. Referring to Fig. 1, there is shown the presser bar 20, needles 21 and guide head 22 of a 80 known type of sewing machine. At its lower end, presser bar 20 has a presser foot 23 grooved on its under side for passage of the welt, as indicated at 24, 25 in Fig. 3 and having perforations 26 for the two needles 90 (Fig. 2). The presser foot 23 bears against a plate 27 designed to support the welt during the sewing operation, and by means of the pressure of a strong spring 28 (Fig. 1), shapes the deformable core 13 to final form 95 in which it is held by the longitudinal row of stitches and by the natural stiffness of the cover material 12. The machine stitches the welt longitudinally as at 29, Figs. 2 and 8, to provide two small marginal beads and a 100 large central bead lying between them.

An adjustable set collar on rod 20 for transferring pressure from spring 28, permits an adjustment of the pressure of foot 23 to vary somewhat the firmness and final shape 105 of the central bead. The welt is particularly

easy to secure because the central bead is hinged, as illustrated in Fig. 9, and may be lifted out of the way until the securing elements 31 are driven, thereafter closing over 5 and completely hiding such elements.

Obviously the present invention is not restricted to the particular embodiment thereof herein shown and described. Moreover, it is not indispensable that all the features 10 of the invention be used conjointly since they may be employed advantageously in various combinations and sub-combinations as defined in the claims.

Having described one embodiment of my 15 invention, I claim:

1. In a finishing welt, a finishing bead comprising in combination a core consisting of a strand of loosely twisted fiber and covering material surrounding said core and constructed 20 and arranged to hold said core in firmly

compressed condition and in a shape to give the bead the desired contour.

2. As an article of manufacture, a finishing welt having a bead formed of flexible covering material enclosing a core consisting 25 of a compressed strand of twisted jute fibers.

3. As an article of manufacture, a finishing welt having a core consisting of a strand of loosely twisted jute fibers in firmly compressed condition.

4. As an article of manufacture, a welt having longitudinal edge beads each with a relatively hard filler; and having a larger intermediate bead with a soft, loosely twisted, jute fiber filler compressed to make said bead 30 firm.

In testimony whereof, I have signed my name to this specification.

LESTER B. STROUT.
